UNITED STATES PATENT OFFICE.

JOSEPH G. GROFF, OF CONNERSVILLE, INDIANA.

SAW-GUARD.

SPECIFICATION forming part of Letters Patent No. 284,199, dated September 4, 1883.

Application filed April 12, 1883. (No model.)

To all whom it may concern:

Be it known that I, JOSEPH G. GROFF, of Connerville, in the county of Fayette and State of Indiana, have invented certain new and useful Improvements in Guards or Hoods for Circular Saws; and I do hereby declare the following to be a full, clear, and exact description of the same, reference being had to the accompanying drawings, forming part of this specification, and to the figures and letters of reference marked thereon.

This invention relates to that class of guards for circular saws which are automatic in their action, rising upon the approach of the material to be sawed, resting upon the material while being sawed, and dropping back upon or near to the surface of the table after the material has passed from under it, the saw being all the while covered and the operator protected from accident.

I will first describe the construction of my improved saw-guard, and will then point out those particular features of it which I deem to be novel in view of the present advanced state of the art.

Referring to the accompanying drawings, Figure 1 represents a side elevation of my invention. Fig. 2 is an edge view of a portion of the device looking from the rear.

Similar letters of reference in the several figures denote the same parts.

A represents the hood or guard proper, provided at its front with an upwardly-projecting arm, *a*, and at its rear with a downwardly-inclined continuation or extension, *b*, by which it is secured to the blade or shank B by rivets or equivalent fastenings, as shown. When in normal position the forward end of the hood rests at *c* upon or is adjusted near to the top of the table, the bottom line of the hood, from *c* to *c'*, making an acute angle with the top of the table, and the lines *c c'* and *c' d'* together making an obtuse angle, all as shown in Fig. 1.

The shank B consists of a metal blade riveted to the extension of the hood proper, as before mentioned, and extending downward and backward, and fitting within a socket formed of backwardly-inclined plates C C', depending from the bed-plate E, as shown. At its lower end the shank or blade B is bifurcated or slotted longitudinally, as shown in Fig. 1, for the

accommodation of a grooved roller, T, mounted upon a pin or bolt between the socket-plates C C', and also for the accommodation of a cross-rod, D, passing laterally through a vertical slot, *g*, in the socket-plate C, and through one of a series of holes, *g'*, in the other of said socket-plates C', as shown in Fig. 2. The cross-rod D is provided with a guard or collar, *h*, which limits the extent to which the end of the rod can be inserted through the plates C C'; and it is further provided with an annular recess or groove, *s*, near its extreme inner end, at the point where it passes through the hole in the plate C', the edge of the opening in said plate C' being adapted to engage with said groove when the rod is in position, so as to prevent the casual longitudinal displacement of the latter. The shank of the rod extends to the side of the table, and is provided with a suitable handle, D', arranged in convenient reach of the operator. When the shank or blade B is slipped into the socket formed by the plates C C', its forward edge rests within the groove of a flanged roller, *r*, near the top of the socket, while against its rear edge presses a spring, *m*, preferably carrying a grooved roller, *m'*, and projecting forward from a support, *n*, as shown in Fig. 1. The flanged roller on the one side, and the spring, with or without its roller *m'*, on the other side, assisted by the lower grooved roller, T, therefore serve to guide and steady the shank in its up and down movements. The shank, in addition to its capability of being moved up and down, has a limited back and forth swinging motion upon the roller T as a pivot, the open ends of the socket and the slot in the bed-plate at *e* permitting of such motion. Rod D serves as the means for limiting the downward movement of the shank, and consequently the normal vertical position of the hood with respect to the table, for it is evident that by loosening the rod and adjusting it up or down in one or the other of the holes *g'* in socket-plate C' the hood will be raised or lowered, and its lowest position with respect to the table will be determined. This capability of adjustment enables the hood to be so positioned as that the material to be sawed will be required to automatically raise it the minimum distance in passing under. Ordinarily I find it only nec-

essary to adjust the hood so that its forward end, at *c*, shall stand a quarter of an inch below the height or thickness of the material to be sawed. The material will then be required to 5 raise the hood but a quarter of an inch.

The operation of the device will be apparent. The advancing material to be sawed—a board, for instance—strikes the upper arm, *a*, of the hood and raises the forward end of the 10 hood, and at the same time causes the hood to swing backward slightly upon the roller *T* as a pivot, then, farther advancing, it strikes the downwardly-inclined extension *b* and raises the rear of the hood. While the material 15 passes by the saw the hood rests upon it and remains there until the end of the board is reached, when the hood settles back to its normal position, its front end dropping back upon the table first, and then its rear end.

20 It will be observed that the backward inclination of the shank or blade *B*, as well as that of the socket-plates *C C'*, enables the rear of the table to be raised or lowered without liability of the parts beneath the table coming 25 in contact with the saw.

Having thus described my invention, I claim as new—

1. The hood having the forward upwardly-inclined extension against which the lumber 30 strikes to raise the front of the hood, and having the rearward and downwardly inclined extension against which the lumber strikes to raise the rear end of the hood, in combination with the blade or shank riveted to said extension, and the socket for the blade, substantially as described.

2. The combination of the hood, the depending shank or blade attached to the hood and

slotted longitudinally at its lower end, the socket for receiving the shank or blade, and 40 the cross-rod working in the slot, substantially as described, for the purpose specified.

3. The combination of the hood, the slotted blade or shank, the socket-plates, one having the vertical slot and the other the adjusting- 45 holes, with the vertically-adjustable cross-rod, substantially as described.

4. The combination of the hood, the longitudinally-slotted blade or shank attached to and moving with the hood, the plates constituting the socket for the shank, the cross-rod working through the slot in the shank, and the spring bearing against the back of the shank and operating to keep the latter normally tilted forward, though adapted to yield when the 55 shank is tilted backward, substantially as described.

5. The combination of the hood, the longitudinally-slotted blade or shank attached to and moving with the hood, the socket for the 60 shank, the cross-rod, the flanged roller at the front and the spring at the back of the shank, said roller and spring serving to keep the shank in proper position laterally while being tilted, substantially as described.

6. The combination of the hood, the slotted blade attached to and moving with the hood, the socket-plates, the cross-rod, and the grooved roller on the cross-rod, said roller operating to assist in guiding the shank while 70 being tilted, substantially as described.

JOSEPH G. GROFF.
